UNITED STATES PATENT OFFICE

2,534,514

SAFETY DEVICE FOR FIREARMS

Hans P. Hansen, Bronx, N. Y.

Application April 14, 1948, Serial No. 20,972

1 Claim. (Cl. 42—70)

1
This invention relates to a new and useful improvement in safety devices for firearms and more especially for shotguns.

It too often happens that when a party is hunting someone in said party gets hurt or killed due to the fact that the safety means, which is supposed to prevent the movement of the trigger, when the gun is not in use, has by forgetfulness not been applied, or by mistake withdrawn, with the result that serious accidents happen.

Then again, quite often a hunter misses an opportunity to deliver, or fire a shot that would have been sure to bring down the game hunted, just because the safety lock was applied to the trigger when in fact the hunter thought it had been released.

The safety device now conventionally used on all makes of shotguns consists of a sliding mechanism, inserted through an elongated aperture in the upper part of the gun's lock-housing, and is so arranged that its lower extension meets the upper extension of the trigger plate proper, when the safety device is set at "safe," and thus prevents the trigger from releasing the cocked hammer and thereby the firing of the gun. The upper part of said safety device is constructed as a catch or latch-button which is manually operated by the gunner at will; but the fact that the safety in this case depends upon the memory or care exhibited by the respective user of a loaded gun is what makes the conventional safety device unsafe and dangerous. With this invention the gun can only be fired when the gun-butt plate is thrown into contact with the shoulder of the gunner.

With the above and other objects in view, this invention consists of the novel features of construction, combination and arrangement of parts, herein after fully described, claimed and illustrated in the accompanying drawings forming part of this application, and in which similar characters of reference indicate corresponding parts in all views, and in which:

Figure 1 is a longitudinal side view of my invention, partly in elevation, and partly in section.

Figure 2 is a view similar to Figure 1, but showing further details of construction.

Referring more particularly to the drawing, 10 indicates the gun stock, in which my device is housed; 11 indicates the conventional safety lock inserted through an elongated aperture in the upper part of the gun's lock-housing, not further described herein, as this is a conventional arrangement; 12 indicates the also conventional

part by which said safety lock is operated; the said part 12 may, however, be omitted in any new construction; 13 indicates the conventional trigger, while no elaboration is thought necessary in regard to the said conventional parts and their relative arrangement, my device lies substantially in the gun stock.

The gun stock 10 is having the bore 14, which is adapted to have sliding therein the rod 15; a member 40 is by a swivel connection 41 secured to the rod 15 and adapted for adjustment relative to the latter; said member 40 is connected to the safety lock 11.

At the other end of the rod 15 the latter is provided with a second swivel connection 42 for attaching said rod 15 to a short portion 43, whereby to obtain horizontal adjustment of the rod; the portion 43 is in turn connected to the shaft 48 in any suitable manner.

20 A shoulder contact 53 is mounted in a housing 63, a bracket 64 is attached to the lower end of the housing and secured to the gun stock and housing by a screw 65; a spring 56 is mounted on the shaft 48, a washer 57 abuts the other end of the spring and rests against an enlargement 58 of the shoulder contact 53.

The shoulder contact 53 is pivoted in the housing, as shown at 66, a pin 59 is fastened through the shaft 48 to the shoulder contact 53.

The bracket 64 is at its upper end formed with an enlarged opening 68, whereby to permit sufficient play for the shaft 48 during operation.

25 A lug 61 is pivotally secured within the housing as at 70, a recess 71 is formed at the bottom of the shoulder contact 53, so that when in an inclining position the lug 61 will drop into said recess 71, and thereby lock the shoulder contact, and thus prevent the safety mechanism from being released.

30 By holding the gun in a substantially horizontal or shooting position, the lug 61 will rest against a stud 72; when, however, the gun is lowered to the ground, or in a vertical position, the lug 61 will, due to gravity, also drop down to a vertical position, resting against a stud 73, thereby preventing the shoulder contact 53 from pushing the shaft 48 forward to release the trigger, thus leaving the gun in locked position.

I claim as my invention:

In a device of the class described, a gun stock, a shoulder contact pivoted in a housing, a bracket attached to the lower end of said housing, a screw securing said bracket to the housing and the gun stock, a spring mounted on a shaft, said spring abutting at one end a bracket and at the

other end a washer the latter resting against an enlargement of the shoulder contact, a pin through the shaft and shoulder contact, the bracket being provided with an enlarged opening adapted to receive said shaft, a lug pivotally arranged within the housing, a stud disposed within the latter and adapted to arrest the motion of said lug when in horizontal position, the shoulder contact having a recess at the bottom thereof, a second stud the latter being mounted in said recess, said lug being in vertical position adapted to engage said second stud in locking the shoulder contact, thereby preventing the safety mechanism from being released.
